W. HOLLINGSWORTH.
MECHANISM FOR DRYING VARNISHED PAPER.

No. 562,534.

Patented June 23, 1896.

UNITED STATES PATENT OFFICE.

WILLIAM HOLLINGSWORTH, OF BALTIMORE, MARYLAND.

MECHANISM FOR DRYING VARNISHED PAPER.

SPECIFICATION forming part of Letters Patent No. 562,534, dated June 23, 1896.

Application filed March 31, 1894. Serial No. 505,884. (No model.)

To all whom it may concern:

Be it known that I, WILLIAM HOLLINGSWORTH, a citizen of the United States, residing at Baltimore city, in the State of Maryland, 5 have invented new and useful Improvements in Mechanism for Drying Paper which has been Treated with Varnish, Size, or other Material, of which the following is a specification.

My invention relates to mechanism for drying paper which has been treated with varnish, size, or other material, and especially for drying labels after the same have been newly printed or varnished.

It is my purpose to provide a simple apparatus by which the labels, sheets, or similar material may be transferred from one conveyer-belt to another without exposing the printed, varnished, or otherwise coated surface to contact and without folding, twining, 20 or wrinkling the sheet.

It is my purpose, also, to provide a transferring mechanism consisting of a series of transfer-tapes having independent action, and a flier-frame adapted to receive the sheet from 25 a conveyer-belt and deposit it upon the transfer-tapes, which carry it upon a second conveyer-belt moving in the same direction with said tapes, but opposite to the movement of the first conveyer-belt.

30 The invention consists, to these ends, in the parts and combinations of parts herein-after fully described, and then particularly pointed out in the claims.

Referring to the accompanying drawings, 35 Figure 1 is a side elevation of a portion of one end of a drying-chamber containing a series of oppositely-moving conveyer-belts, of the usual form, my invention being shown in full lines as incorporated with known parts 40 shown by dotted lines. Fig. 1^a is a similar view of a portion of the opposite end of the drying-chamber. Fig. 2 is a plan view of the flier-frame and transfer-tapes at one end of the drying-chamber, together with a portion 45 of one of the conveyer-belts.

The reference-numeral 1, in said drawings, indicates the drying-chamber, which contains a series of horizontal conveyer-belts 2, carried by rolls 3, and arranged one beneath another 50 with a suitable space between. I have shown three of these conveyer-belts in the drawings, but it is evident that any desired number may

be employed. Said belts are driven at suitable speed in opposite directions, as indicated by the arrows in Figs. 1 and 1^a. The sheets, 55 after treatment, are carried to and delivered upon the surface of the upper conveyer-belt by means of tapes 4 and 5 or by any other mechanism preferred, these parts forming no portion of my invention. At the other end 60 of the drying-chamber 1 I arrange a series of transfer-tapes 6, carried by rolls 7 and 8 in a direction of movement contrary to the travel of the first conveyer-belt. The roll 7 is preferably arranged just above the surface 65 of the second conveyer-belt and between the end of the same and the end of the first, or upper, conveyer-belt, but may be located at any point at which the transfer-tapes carried by it will be enabled to deliver a sheet 70 lying upon them to the second conveyer-belt, which moves in the same direction with the tapes, but opposite to the first conveyer-belt. The rolls 8 consist of independent spools, each supported by a bracket 9, adjustably mounted 75 on a rod 12 by means of a set-screw 13, which passes through one of two lugs 14 on the bracket and engages the rod, the latter being supported upon posts at a suitable distance from the end of the conveyer-belt. Upon the 80 same posts is mounted a rock-shaft 15, arranged somewhat beneath the rolls 8, and upon said rod are mounted rigidly a series of flier-rods 16, provided with adjustable stop-pins 85 and arranged at such intervals as to alternate with the transfer-tapes 6.

By rocking the shaft 15, the flier-rods 16 will be vibrated through an arc of a circle, and the rods, which constitute a structure substantially similar to a flier-frame, may be 90 caused to occupy, alternately, the positions shown in dotted and in full lines in Figs. 1 or 1^a. When in the position shown in full lines, the free ends of the flier-rods will lie nearly in line with the axis of the roll 3, carrying the upper 95 conveyer-belt, and in position to receive the sheet carried by the same. When in the position shown by dotted lines, the flier-rods will lie beneath the transfer-tapes 6, or between the parallel portions of said tapes and 100 in substantial parallelism with them, the sheet being thereby laid upon said tapes and removed from the flier-rods. The movement of the transfer-tapes now carries the sheet

upon and delivers it to the second conveyer-belt, which travels in the same direction and thus preserves the continuity of the sheet.

The rock-shaft 15, carrying the flier-rods 16, 5 is operated by a rod 17, one end of which is adjustably connected to a slotted lever-arm 18 on the rock-shaft 15. A spring 19 normally draws said rod in a direction to swing the flier-rods into the position shown in dotted 10 lines, the rod having such length that it extends throughout the length of the drying-chamber and is connected, at its other end, to a lever-arm 20, supported by a rock-shaft 21. The lever-arm is operated by a cam 22, carried by a shaft 23, which is operated by a sprocket 24, the mechanism employed being of any familiar type.

A second transfer mechanism, similar in all 20 substantial points to that already described, is arranged to receive the sheets from the second conveyer-belt and deliver them to a third conveyer. This second mechanism is operated like the first, a cam 22 being at the other end of the shaft 23.

25 The drying-chamber is provided with a steam-coil or other suitable means for imparting heat and the conveyer-belt which last receives the sheets is preferably arranged below the heating devices, in order that they 30 may have an opportunity to cool. The sheets are delivered from it automatically to an inclined shelf 25.

What I claim is—

1. In an apparatus for drying paper, the 35 combination with an upper and a lower conveyer-belt of a series of transfer-tapes coöperating with the lower conveyer-belt and a series of flier-rods adapted to support the paper from the upper conveyer-belt to the transfer-tapes, said flier-rods in their raised position being inclined at an angle to the upper conveyer-belt and in their lower position below and substantially parallel with the surface of the transfer-tapes, substantially as 40 described.

45

2. In an apparatus for drying paper, the combination with a series of conveyer-belts moving successively in opposite directions and arranged one beneath the other, of a transfer mechanism consisting of transfer-tapes, a series of flier-sticks rigidly mounted on a rock-shaft and adapted to pass between said tapes, and means for automatically operating the rock-shaft at proper intervals, substantially as described. 50

3. In an apparatus for drying paper, the combination with an upper and a lower conveyer-belt, of a series of transfer-tapes adapted to coöperate with the lower conveyer-belt, a series of flier-rods adapted to support the paper from the upper conveyer-belt to the transfer-tapes, said flier-rods in their raised position being inclined at an angle to the upper conveyer-belt and in their lower position below and parallel with the surface of the 60 transfer-tapes, a rock-shaft upon which said flier-rods are rigidly mounted, a lever-arm on said rock-shaft and automatic cam mechanism adapted to operate said arm at intervals, substantially as described. 55

4. In an apparatus for drying paper, the combination with an upper and a lower conveyer-belt traveling in opposite directions, of a series of transfer-tapes having continuous movement in the same direction with the 70 lower conveyer-belt, a series of flier-rods, a rock-shaft on which the flier-rods are rigidly mounted, a lever-arm linked to an arm on said rock-shaft, a cam operating said lever-arm and means for periodically operating the 75 cam, substantially as described.

In testimony whereof I have hereunto set my hand and affixed my seal in presence of two subscribing witnesses.

WILLIAM HOLLINGSWORTH. [L. S.]
